T. B. BALDWIN.
Parlor Cooking-Stove.

No. 225,783.

Patented Mar. 23, 1880.

The diagram shows a horizontal beam of length l supported by two vertical columns. The left column is labeled x and the right column is labeled h . A central vertical force F is applied to the beam. The beam is divided into three segments by the supports and the central load: a left segment from the left end to x , a middle segment from x to h , and a right segment from h to the right end.

UNITED STATES PATENT OFFICE.

THOMAS B. BALDWIN, OF TROY, PENNSYLVANIA.

PARLOR COOKING-STOVE.

SPECIFICATION forming part of Letters Patent No. 225,783, dated March 23, 1880.

Application filed December 23, 1879.

To all whom it may concern:

Be it known that I, THOMAS B. BALDWIN, of Troy, Bradford county, and State of Pennsylvania, have invented a new and Improved 5 Parlor Cooking-Stove, of which the following is a specification.

Figure 1 is a perspective view of the stove. Fig. 2 is a sectional elevation of the same on line x x , Fig. 1; and Fig. 3 is a perspective 10 view of the grate-cover.

Similar letters of reference indicate corresponding parts.

The object of this invention is to provide a stove with two fire-places, so arranged that 15 the one may be used simply for heating purposes and the other be used for cooking purposes.

In the drawings, A represents the cylinder 20 of the stove, provided with a door, a, for the lower fire-chamber, B, and a door, b, for the upper or cooking chamber, C, said stove being also provided with a draft-opening, c, for the lower, and a draft-opening, d, for the upper, fire-chamber or cooking part of the stove.

25 Fixed horizontally within the stove, between the lower and upper doors, a b, is a grate, D, provided with a grated or perforated back, f, fixed vertically along its rear edge, in order to retain fuel upon the said grate, and between 30 the rear edge of this grate D, which is cut away for the purpose, and the back of the stove there is formed a flue, H, which permits the passage of the products of combustion from the lower fire-chamber to the smoke-pipe E.

The top F of this stove is hinged, as shown 35 at h, so that it can readily be turned back, and it is provided with holes m m for the accommodation of cooking utensils, said holes m m being closed with suitable covers when not filled with cooking utensils.

40 When this stove is used as a parlor-stove simply for heating the room, the fire is placed only in the lower fire-chamber and on a suitable grate; but when used for cooking a fire is placed on the upper grate, D, so that the 45 heat therefrom may be brought in close contact with the bottom of the cooking utensils.

Both fires may be maintained at the same time, and in such case the plate G will not be used; and when a fire is made in only the lower 50 part of the stove the upper fire-place may be converted into a heating-oven by placing the said grate-cover G upon the upper grate, D.

Having thus described my invention, I claim as new and desire to secure by Letters Patent—

55 A parlor cook-stove consisting of a single cylinder, having the doors a b, draft-openings c d, grate D f placed between said openings, smoke-pipe E, holes m in top F, and flue H, 60 all arranged substantially as shown and described.

THOMAS BURT BALDWIN.
